SWITCH CONTROL MEANS FOR SLICING MACHINES

Morris Brustowsky, Brooklyn, N. Y., assignor to
U. S. Slicing Machine Company, La Porte, Ind.,
a corporation of Indiana

Original application May 8, 1942, Serial No.
442,186. Divided and this application December
22, 1942; Serial No. 469,797

8 Claims. (Cl. 146—102)

1

This invention relates to improvements in a switch control mechanism for slicing machines and this application is a divisional application taken from my previous copending now abandoned application for Slicing Machine, Serial Number 442,186, filed May 8, 1942.

Slicing machines of the type employed for slicing meats, bread and similar commodities employ a motor driven knife and a supporting table upon which the article being sliced is mounted.

The supporting table is movable towards and away from the knife to bring the article to be sliced, into operative relation to the knife.

In the more modern slicing machines, the movement of the supporting table relative to the knife may be effected either manually, or by a mechanism which in turn is operated by the same motor which is employed to drive the knife.

It is to the aforementioned type of slicing machine that the present invention pertains.

Such machines, as aforementioned, employ a mechanism which may be operatively connected with the motor which drives the knife when it is desired to operate the table by power.

This operative connection between the table operating mechanism and the motor generally consists of a clutch which may be operated from the front of the machine.

In such machines, it is highly desirable to have the table operating mechanism out of operative engagement with the motor at all times that the motor is not in operation.

This is true for the reasons that, first, it relieves the motor of the load incidental to operation of the table upon starting of the motor; and second, it prevents injury to the operator by unexpected operation of the table immediately when the motor starts operation.

It is one object of the present invention to provide a control mechanism whereby the table operating mechanism is never operatively connected with the motor when the motor is at rest.

It is another object of the invention to provide a control mechanism in which the switch which controls the circuit to the motor cannot be operated to close the circuit of the motor if the table operating mechanism is operatively connected with the motor.

It is still a further object of the invention to provide a control mechanism which, when the motor is in operation and the table operating mechanism is operatively connected to the motor, the circuit of the motor cannot be opened to stop the motor until after the table operating mechanism has been disconnected from the motor.

2

It is a still further object of the invention, so to construct the control mechanism that the circuit to the motor may be opened or closed at will, so long as the table operating mechanism is not operatively connected with the motor, thus permitting of driving the knife by the motor and manual operation of the table independently of the table operating mechanism.

With the above objects in view, reference will now be had to the following specification and claims, and the accompanying drawings, in which,

Figure 1 is a longitudinal sectional view taken from front to rear of a conventional type of slicing machine illustrating a portion of the control mechanism of the present invention;

Figure 2 is a detail plan view of the machine, parts being broken away illustrating the motor and the mechanism by which the knife is driven thereby;

Figure 3 is a fragmentary vertical sectional view illustrating a portion of the table operating mechanism and the clutch by which it is operatively connected to the motor, and;

Figure 4 is a detail view partly in elevation and partly in section illustrating the control switch of the motor and its operative connection with the clutch operating element.

Figure 5 is a detail transverse sectional view on the lines 5—5 of Figures 1 and 2;

Figure 6 is a detail sectional view on the line 6—6 of Figure 5; and

Figure 7 is a detail horizontal sectional view on the line 7—7 of Figure 6.

Referring to the drawings by reference character and particularly to Figure 1, 5 designates the base of the machine, said base preferably being hollow as illustrated.

Depending from the base, there are two partitions or walls 6 and 7, and slidably mounted in these walls, and extending through an opening 9 in the front wall 8 of the base, there is a rod 10. Beyond the front wall 8 of the base, the rod 10 is supported in a sleeve bearing 25 mounted upon the outer face of the front wall 8 and upon its outer extremity, the rod 10 is provided with an operating knob 18.

As illustrated in Figure 1, the rod 10 is provided with an annular groove 17 which, when the parts are in the positions illustrated in Figure 1, occupies a position within the sleeve bearing 25.

Upon its inner end, the rod 10 carries a cam member 20 which has a cam surface 21 which terminates at its upper end in a curved seat 16.

Referring to Figure 2 of the drawings, the reference character 15 designates an electric motor

and through the medium of a flexible coupling 14, this motor drives a shaft 12 upon which the knife 11 is mounted. Also carried by the shaft 12, there is a driving worm 13 which meshes with and drives a worm gear 32 mounted upon a shaft 28. The slicing knife 11 is rotatably mounted at the rear of the machine and is driven by the shaft 12 by means of suitable belt and pulley arrangements within the housing 9, Figure 2.

As best illustrated in Figure 3 of the drawings, the shafts 12 and 28 pass through a housing 29 in right angular relation to each other and the gears 13 and 32, heretofore mentioned, are enclosed within said housing.

Further referring to Figure 3, it will be noted that the shaft 28 extends beyond the bottom wall of the housing 29 and loosely mounted upon the extended end thereof, there is a pulley 24 around which passes a belt 34.

The belt 34 operates the table driving mechanism which is also disclosed in my copending application Serial Number 523,009, filed February 19, 1944, which became Patent Number 2,412,079 on December 3, 1946, as a continuation of application Serial Number 442,186, filed May 8, 1942.

A reciprocating table or support lies over the base of the machine and is adapted for reciprocation in a rectilinear path past the slicing knife 11. One side of the table has secured thereto a sleeve-like bearing which is slidably mounted upon a rod 18 and extends longitudinally within the base 5 of the machine. The other side of the reciprocating table carries a roller 19 which rests upon a rod 20, which rod extends longitudinally inferiorly of the base and on the left side of the machine.

When the motor 15 is operating the knife 11 will be rotated and the reciprocating table is adapted to be moved freely by hand back and forth out of and into operative relation with the knife in such a manner that slices of the article operated upon may be cut by the knife.

Means employing the power of the motor 15 to reciprocate the table includes the pulley 24 and an additional pulley 23. The pulley 23 is carried by a vertically disposed shaft or bolt mounted in a plate or bracket secured within the front part of the base of the machine. The belt 34 is disposed in a horizontal plane within the base of the machine and is supported by and passes around the pulleys 23 and 24.

An arm 36 depending from the sleeve-like bearing is secured by bolts 35 or the like. The lower end of the arm 36 carries a housing 37, one side of which is removably secured to the housing by bolts 39 or the like.

The flights 42 and 43 of the belt 34 pass through the housing 37 and inwardly with respect to pinch blocks 40 and 41 which are carried by the housing 37.

A star wheel 44 mounted within the casing 37 and disposed between the flights 42 and 43 of the belt 34 is freely rotatable upon a shaft 45 and has arms 46 extending radially therefrom in equally spaced relation to one another.

Means to limit the rotary movement of the star wheel 44 to a step by step motion includes two pins 47 and 48 carried by the housing 37 at diametrically opposite points of the star wheel 44.

The pins 47 and 48 are of such length that when they are moved inwardly of the housing they extend between the arms of the star wheel to prevent rotation thereof but to permit rotation thereof when they are withdrawn from the housing.

The pins 47 and 48 are alternately moved inwardly and outwardly of the housing by two stationary cams 50 and 51 carried by the base of the machine. Cam 50 is located just in advance of the pulley 23, whereas cam 51 is located just in advance of the pulley 24.

Each of the cams 50 and 51 consists of a bar having a beveled face 52 upon its free end and each of the pins 47 and 48 has a head 53 upon its outer end.

The pins 47 and 48 are normally forced inwardly of the housing 37 by means of springs 54 and the beveled faces of the cams are adapted to engage behind the heads of the pins to withdraw them from the housing against the action of said springs 54.

When the belt travels in the direction indicated by the arrows A in Figure 7, the star wheel 44 moves in a step by step motion in a clockwise direction as indicated by the arrow B in said figure.

The arms 46 of the star wheel 44 are of such length that when one of them is disposed at right angles to one of the flights of the belt, it will bite the belt and pinch it against the corresponding pinch block 40 or 41, thus locking the housing 37 to one of the flights of the belt and causing it to move in the direction of movement of that flight of the belt to which it is locked.

Operation of table drive

In Figure 7, the housing 37 is illustrated at substantially the end of its movement to the left with one of the arms 46 in engagement with the pin 48 and also biting the flight 43 against the pinch block 41. At this point, the pin 48 engages the cam 50, the beveled edge 52 of which rides beneath the head 53 of the pin 48 and withdraws the pin 48 outwardly of the housing 37 and out of engagement with that arm of the star wheel which is shown as biting the flight 43 of the belt against the pinch block 41.

As soon as the pin 48 has been disengaged from the star wheel, the star wheel is free to move in a clockwise direction as indicated by the arrow B. As the star wheel starts to rotate, the bite between the arm 46 thereof and the pinch block 41 is relieved and that arm 46 of the star wheel which is shown at the left of the center in Figure 7 moves first into engagement with the flight 42 of the belt, biting it against the pinch block 40. As the star wheel continues to rotate, the last mentioned arm 46 thereof engages the pin 47 to arrest rotation of the star wheel 44 and to lock the housing 37 to the flight 42 of the belt.

By locking the housing 37 to the flight 42, the belt moves the housing to the right until it reaches the full extent of its movement in this direction. While the housing moved towards the right, the pin 48 (Figure 7) cleared the cam 50 and was again projected into the housing under the influence of its spring 54, thus positioning it in the path of the next arm of the star wheel which is to bite the flight 43 of the belt when the housing 37 reaches the full extent of its movement to the right.

When the housing has reached its extreme right hand position, the beveled face 52 of the cam 51 (Figure 5) engages behind the head of the pin 47 and withdraws it to a point where it disengages the star wheel and permits it to turn another step in the clockwise direction to move that arm illustrated at the right of the center into biting engagement with the flight 43 of the belt and into engagement with the pin 48 to

lock the housing 37 to the belt 34 and move the housing again to the left.

Also carried by the extension of the shaft 28, and operatively connected thereto, there is a clutch member 60 which is moved into and out of clutching engagement with the pulley 24 by means of a clutch fork 61.

The clutch fork 61 is rigidly carried by the inner face of a right angular end extension 62 of a lever 63 which is pivotally mounted as at 64 and which carries a roller 68 that rides the cam face 21 of the cam member 20 as the rod 10 is operated and which comes to rest in the curved seat 16 of the cam member when the rod 10 is in its innermost position as illustrated in Figure 1.

Extending from the outer face of the right angular end extension 62 of the lever 63, there is a hooked arm 66 and extending from the housing 29 at a point substantially above the hooked arm 66, there is an arm 67.

Connected at one of its ends to the hooked arm 66 and at its other end to the arm 67, there is a coil spring 65, the tension of which tends at all times to rock the lever 63 about its pivotal point 64 in the proper direction to move the clutch member 60 into clutching engagement with the pulley 24.

By reference to Figures 1 and 3, it will be obvious that when the rod 10 is in its innermost position as shown in Figure 1 and the roller 68 of the lever 63 is at rest in the seat 16 of the cam member 20, the lever 63 will be held in such position that the clutch member 60 will be disengaged with relation to the pulley 24 and the table operating mechanism is not operatively connected with the motor, but is free for manual operation.

Still referring to said figures, it will be noted that if the rod 10 be pulled outwardly of the base or to the left in Figure 1, the roller 68 of the lever 63 will leave the seat 16 of the cam member 20 and ride down the cam surface 21 thereof.

As the roller 68 rides down the cam surface 21 of the cam member, thus permitting movement of the lever 63 about its pivotal point 64 under the influence of the spring 65, to move the clutch member into clutching engagement with the pulley 24 thereby to operatively connect the table operating mechanism with the motor. 15

In said Figure 4, the switch is illustrated in dotted lines in its "on" or circuit closing position, and in full lines, in its "off" or circuit opening position.

Pivoted connected as at 72 to the switch toggle lever 70, there is a latch rod 73 which extends through a passage 74 in the sleeve bearing 25 in a plane above the plane of the rod 10 and directly over the annular groove 17 thereof, and in a direction at right angles to said rod 10.

Near its free end, the latch rod 73 is provided with a cut out portion 75, the purpose of which will hereinafter appear.

With the parts in their positions as illustrated in Figure 1, and in full lines in Figure 4, the circuit of the motor is open and the machine is at rest with the pivoted lever 63 in that position in which it holds the clutch element 60 against clutching engagement with the pulley 24.

With the parts in these positions, the latch rod 73 rests in the annular groove 17 of the rod 10, see Figure 4, thus locking the same in its innermost position and thereby preventing operation of the clutch member 60.

Upon movement of the switch lever 70 to the dotted line position in Figure 4, the circuit to the motor is closed and operation of the motor and the knife 11 begins.

In this position of the parts, the table is not operatively connected to its operating mechanism but is free for manual operation.

Upon movement of the switch lever 70 to the "on" position, the latch rod 73 is also moved to the left in Figure 4 to a position where its cut out portion 75 overlies the annular groove 17 of the rod 10. In this position of the latch rod 73, the rod 10 may be moved outwardly of the base to permit rocking of the lever 63 above its pivotal point to operatively connect the clutch member 60 with the pulley 24, as heretofore described, thereby to connect the table operating mechanism with the motor to operate the table by power.

It will now be apparent that if the rod 10 is moved outwardly to effect operative engagement of the clutch member and pulley, the annular groove 17 of the rod moves out of the cut out portion 75 of the latch rod 73 and a portion of the rod 10, which portion is of full diameter, passes into the cut out portion 75 of the latch rod 73, in which position of the rod 10, the latch rod is locked against operation by the switch lever by reason of the fact that upon attempt to move the switch lever 70 of the switch to the right, the end wall 76 of the cut out portion 75 of the latch rod will engage the rod 10 and thus prevent operation of the switch lever. Thus, the circuit to the motor cannot be opened so long as the rod 10 is in its outermost position and the table operating mechanism is operatively connected with the motor.

If however, with the machine in operation, with the table operating mechanism operatively connected with the motor, the rod 10 is moved inwardly of the base to disconnect the table operating mechanism, the annular groove 17 of the rod 10 comes to position beneath the latch rod 73 and permits of its passing through said groove upon attempt to move the switch lever 70 to its "off" position and open the circuit of the motor 15.

Thus, it will be apparent that when the machine is at rest, the table operating mechanism cannot be operatively connected with the motor until after the switch has been operated to close the motor circuit and that once the table operating mechanism has been operatively connected with the motor, the switch cannot be operated to open the motor circuit until after the table operating mechanism has been disconnected relative to the motor.

Having thus described the invention, what is claimed as new is:

1. A control mechanism for a food slicing machine having a knife and a supporting table movable toward and away from the knife to bring the article being sliced into operative relation to the knife and embodying an electric motor, a clutch in a transmission adapted to transmit power from said electric motor to said table, a first control device to control the starting and stopping of said electric motor, a second control device being separately operable from the first control device and adapted to control the engagement and disengagement of said clutch, and interlocking means between said control devices, said interlocking means embodying a recess in one of the control devices in which a portion of the other control device slides, and the other control device having a recess movable into and out of register with the first said recess, and operating to permit the engagement of said clutch only when the first control device is in a predetermined po-

sition and to permit the stopping of the motor only when the second control device is in its disengaged position.

2. A control mechanism for a food slicing machine having a knife and a supporting table movable toward and away from the knife to bring the article being sliced into operative relation to the knife and embodying an electric motor, a clutch in a transmission adapted to transmit power from said electric motor to said table, a first control device being adapted to control the starting and stopping of said electric motor, a second control device being separately operable from the first control device and being adapted to control the engagement and disengagement of said clutch, and interlocking means between said control devices, said interlocking means embodying a recess in one control device in which a portion of the other control device slides, and the other control device having a recess movable into and out of register with the first said recess, and operating to permit the engagement of said clutch only when the first control device is in a predetermined position.

3. In combination with a slicing machine having a slidable reciprocable carriage movable in a rectilinear path, and a motor driven rotatably mounted knife, disconnectible means between the motor and carriage to permit the carriage to be reciprocated by the motor, a control mechanism to start and stop the motor, and interlocking means between the control means and disconnectible means, said interlocking means embodying two elements, one of which is provided with a recess in which the other element slides, and the other element having a recess movable into and out of register with the first said recess, whereby to permit stopping of the motor only when the carriage is not in motor driving connection with the disconnectible means.

4. In combination with a slicing machine having a slidable reciprocable carriage movable in a rectilinear path, and a motor driven rotatably mounted knife, a control means for the motor to start and stop the motor, disconnectible transmission means between the motor and carriage to permit a driving connection between the motor and the carriage to allow the carriage to be reciprocated by the motor, and an interlock between the transmission means and the control means, said interlock embodying two elements, one of which is provided with a recess in which a portion of the other element slides, and the other element having a recess movable into and out of register with the first said recess, whereby to prevent stopping and starting of the motor when the transmission means is in driving connection with the motor.

5. In combination with a slicing machine having a slidable reciprocable carriage movable in a rectilinear path, a motor driven rotatably mounted knife, a disconnectible transmission between the carriage and motor, a control mechanism to start and stop the electric motor, and interlocking means between the control mechanism and the disconnectible transmission, said interlocking means embodying two elements, one of which is provided with a recess in which a portion of the other element slides, and the other of said elements having a recess movable into and out of register with the first said recess, whereby to

permit connection of the disconnectible means with the carriage only when the control mechanism is in a predetermined position whereby the motor may be stopped only when the transmission mechanism is in disconnected position.
